APPARATUS FOR DRYING PAPER.

1,123,464.

Specification of Letters Patent.

Patented Jan. 5, 1915.

Application filed May 7, 1914. Serial No. 836,841.

To all whom it may concern:

Be it known that we, BERNARD R. ANDREWS and CARLE J. MERRILL, citizens of the United States, and residents of Newton, 5 county of Middlesex, State of Massachusetts, and Portland, county of Cumberland, State of Maine, respectively, have invented an Improvement in Apparatus for Drying Paper, of which the following description, 10 in connection with the accompanying drawing, is a specification, like characters on the drawing representing like parts.

This invention relates to drying apparatus which is especially adapted for use in 15 drying or facilitating the drying of a web of material as it passes over a plurality of rolls, cylinders, or other supporting members. While our invention is capable of use in connection with a variety of drying devices adapted for drying a web as it thus passes over supporting members, yet we have herein chosen to illustrate it as it 20 would be applied to an apparatus for drying a web of paper as it passes through a paper-making machine. It will be understood, 25 however, that the invention is not confined to use in drying paper and that the invention is shown herein as applied to a paper-making machine for illustrative purposes 30 only.

In the manufacture of paper it is customary to dry the web of paper as it comes from the squeeze rolls and before it is delivered to the calendering rolls by passing 35 the paper web over a plurality of heated cylinders, said cylinders being frequently so arranged relative to each other that in passing over them the web forms a plurality of pocket-like spaces between adjacent rolls. 40 One familiar way of arranging the rolls is to place them in two rows, one above the other and in staggered relation so that one series of pocket-like spaces is formed beneath the rolls of the upper set and between 45 the adjacent rolls of the lower set, and another series of pocket-like spaces is formed above the rolls of the lower set and between the adjacent rolls of the upper set.

In the operation of a drying machine of 50 this type the heat of the cylinders causes large volumes of steam to be driven off from the web of paper as it is passed thereover, and to facilitate the drying operation it has been proposed to place nozzles in the various 55 pockets from which drying blasts of air are

delivered against the web forming the sides of the pocket, said blasts of air being produced from a suitable fan or blower.

A paper-making machine is usually provided with a considerable number of drying 60 cylinders, thus forming a corresponding number of pockets, and in order to furnish to the nozzle all the air required to dry the web a blower or fan of considerable size and one requiring considerable power is necessary. 65 Moreover, where the entire current of drying air is delivered from a blower it is difficult to so distribute the air over the web of paper as to produce an even drying 70 in the web, this being partly due to the fact that the drying operation produces considerable volumes of steam which collect in the pockets and prevent the center portion of the web from drying as rapidly as the edges thereof. The drying of the web tends to 75 shrink it somewhat and where the edges dry faster than the center the corresponding shrinkage at the edges is very apt to cause the web to break.

We have endeavored to provide a novel 80 apparatus and method of drying web material by which such material, and especially a paper web, can be dried evenly and rapidly by drying currents of air and with the expenditure of a considerably less 85 amount of power than is necessary where all the drying blast of air is delivered from a blower or fan. We accomplish this object by delivering to each of the pockets a blast of air in such a way that it will induce a 90 current of room air to pass through the pocket from one end to the other whereby the web forming the walls of the pocket is dried partly by the action of the blast of air and partly by the action of the induced 95 current of air. In the preferred embodiment of our invention we provide for subjecting a portion of the area of the web to the combined action of the drying blast or current of air delivered from a nozzle by 100 means of a blower and the current of room air induced by said first-named current of air, and the rest of the area of the web to the action of said induced current of room air alone. By this means an even drying of 105 the web is secured with the use of a comparatively small forced draft. In the preferred embodiment of our invention, we also provide a nozzle device by which a current-inducing, drying air current is delivered 110

against the web forming the walls of each pocket at a point between the edges of the web and at such an angle to the web that said air current will induce a current of room air which will be drawn across the portion of the web not exposed to the current-inducing air current. The combination of these two air currents operates to rapidly dry the web with the expenditure of minimum power. The relation between the nozzle and the walls of the pocket is such that said nozzle and pocket constitute a sort of injector by which a small current of air delivered from the nozzle induces a comparatively large current of room air through the pocket thereby providing for securing the desired rapid drying with a minimum expenditure of power. Moreover, in arranging our device, we propose to deliver the currents into the pockets from the front of the machine and in such a way that the induced currents will also enter the pockets from the front of the machine. As a result, the steam and vapor is carried off at the back of the machine, thus leaving the front of the machine where the operator stands comparatively free from steam.

To facilitate a clear understanding of our invention and its mode of application and operation we have illustrated in the accompanying drawings and we will now describe that portion of a paper-making machine which effects the drying of the paper web and which has applied thereto a practical mechanical embodiment of the invention, but we desire to repeat our statement above to the effect that our invention is not limited in its application and use to a paper-drying machine, but is equally well adapted for use in connection with any drying apparatus for drying a web which passes over a plurality of rolls or cylinders.

In the drawings, Figure 1 is a more or less diagrammatic view of the side elevation of the drying rolls of a paper-making machine showing our improvements applied thereto; Fig. 2 is an end view of Fig. 1; Fig. 3 is an enlarged section through one of the upper pockets on the line $x-x$, Fig. 1, showing the way in which the two currents of air enter and pass through the pockets; Fig. 4 is a side view of a practical nozzle capable of carrying out our invention; Fig. 5 is a section on the line $y-y$, Fig. 4; Fig. 6 is an enlarged section through one of the felt pockets on the line $a-a$, Fig. 1, showing the manner in which the air currents are utilized for drying the felt apron.

We have shown at 1 and 2 a plurality of cylinders, which may be the drying cylinders of a paper-making machine, and over which travels the web 3 that is to be dried. In the construction shown in Fig. 1 the cylinders 1 and 2 are arranged in two rows, one above the other, the cylinders of the upper row

being designated 1 and those of the lower row being designated 2, and the web 3 passes over these cylinders successively. This arrangement of cylinders and web presents a plurality of pocket-like spaces 4 beneath the upper cylinders 1 and between the adjacent cylinders 2, and another series of pocket-like spaces 5 above the lower cylinders 2 and between the adjacent upper cylinders 1, the walls of these pocket-like spaces being formed of the web 3 as it is passing from one roll to another. We will herein-after refer to these pocket-like spaces as pockets.

It is the common practice to employ a felt apron which travels uniformly with the cylinders and which serves to hold the web of paper on the cylinders, thus tending to prevent it from becoming ruptured, and we have herein shown at 6 and 7 two such felt aprons, the apron 6 coöperating with the lower cylinders 2 and the apron 7 coöperating with the upper cylinders 1. These felt aprons are shown as passing over direction rolls 8 situated between the various cylinders. The parts thus far described are such as are commonly found in paper-making machines.

In applying our improvements to a machine of this type we provide means situated exterior to the pockets 4 and 5 and adapted to deliver into them two currents of air, one a current-inducing drying air current which is forced over a certain portion of the area of the web and another a current of room air induced by the first-named current and which is passed over the remaining portion of the web, the two air currents combining to dry the web evenly. The current-inducing air current is delivered into the pockets from nozzles 9 which are situated exterior to the pockets and are preferably located on the front of the machine. We will preferably employ one nozzle for each pocket, although this particular arrangement of nozzles is not essential. Each nozzle is connected by a branch pipe or conduit 10 with a main conduit 11 which leads to a suitable blower or air-forcing mechanism, and we will preferably use two such mains, one situated above and the other below the drying cylinders. The main situated below the drying cylinders is placed in the pit 12 which is usually provided underneath the drying cylinders 1 and 2. We have shown the upper main 11 as supplied with air through a supply pipe 13 which connects to the supply pipe 14 which supplies air to the lower main 11, the supply pipe 14 leading to a suitable blower or air-forcing mechanism. The nozzles 9 are designed so as to deliver a current-inducing air current 15, indicated by the full line arrows, against the web 3 forming the wall of the pocket at a point intermediate of the edges of the web, this

current 15 preferably being so directed that it will strike the web 3 at somewhere near its central portion. Furthermore, this current is directed against the web 3 at an angle thereto, and in such a direction as to induce a current 16 of room air into and through the pocket, said current being indicated by the dotted line arrows. We propose to induce a current-inducing air current against each wall of each pocket so that the web forming each of said walls will be acted upon not only by the current-inducing air current 15, but also by the induced air current 16, as shown best in Fig. 3. The current-inducing air current 15 does not of itself act on the web at the entering end of the pocket but only acts on the web between the central portion of the pocket and the exit end thereof. The induced current 16 of room air acts on the web at the entering end of the pockets and then commingles with the air current 15 and both air currents act on the web from the central portion of the pocket to the opposite edge of the web. This is plainly indicated in the diagram shown in Fig. 3.

A comparatively small current-inducing air current 15 is sufficient when properly directed to induce a current 16 of room air, and inasmuch as only a portion of the volume of air constituting the drying current is delivered by the blower or air-forcing mechanism, the remainder of the drying current being the induced current 16, a considerably less amount of power is required to operate the blower than where all of the drying current is delivered from the blower. Moreover, we find that by delivering the current 15 against the central portion of the web and depending on the induced current 16 of room air for drying the edge of the web adjacent the nozzle, the web will be evenly dried so that there will be no danger of its becoming torn or ruptured because of more rapid drying on the edge than in the center. The walls of the pocket together with the nozzle 9 form a sort of injector by which a small current of air delivered from the nozzle induces a sufficient current of room air through the pocket to effect the desired drying of the web.

With the arrangement of cylinders shown in Fig. 1 it will be seen that the portion of the web between any two cylinders 1 and 2 forms one wall of two adjacent pockets 4 and 5, and since two drying currents of air are introduced into each pocket and against each wall of each pocket, it follows that both sides of each portion of web which is free from the cylinders 1 and 2 and extends from one cylinder to the other is acted upon by the drying currents. This arrangement still further facilitates the drying operation.

The two current-inducing air currents 15 for each pocket can be delivered from a single nozzle by employing a properly con-

structed nozzle and in the drawings we have illustrated a nozzle designed for this purpose, although this construction is not essential to our invention. The nozzle herein shown is provided with two discharge ports 70 or openings 17 situated at an angle to each other and adapted to deliver two diverging air currents 15 herein illustrated. A convenient form of nozzle adapted for this purpose is one provided in its discharge end 75 with the V-shaped deflector 18 which forms a separation between the two discharge ports 17, and serves to give said ports a divergent direction. We may if desired provide the nozzle with means, such as the plates 19, at 80 each side thereof for decreasing slightly the cross-sectional area of the nozzle directly back of the deflector 18, these plates 19 co-operating with the deflector 18 to more positively insure that the currents of air 15 85 will be delivered in the inclined direction desired.

We propose to arrange the nozzle 9 on the front side of the machine, that is, on that side of the machine at which the attendant is 90 situated. The advantage of this construction is that the steam and vapor which is given off from the apparatus during the drying process will be drawn through the pockets by the air currents and delivered therefrom on 95 the opposite side of the machine from which the attendant is located. The attendant is thus situated at all times in air which is comparatively free from steam and vapor. We have also designed the nozzles herein 100 shown so that they will not interfere materially with the operation of handling the paper web to guide it from one roll to another in case the web breaks and it is necessary to thread an end of the web through the 105 various cylinders.

The branch pipes 10 will preferably be placed between the ends of the cylinders 1 and 2, and the front side of the frame 21 in which the cylinders are sustained and said 110 pipes are so designed as to interfere as little as possible with any necessary manipulation of the paper. Each nozzle 9 will preferably be located substantially centrally of its pocket, and each branch pipe 10 is provided with the vertical portion 20 to which the nozzle is secured; with the inclined portion 22 extending across the end of the drum and with the vertical portion 23 connecting to the main 11, the vertical portion being situated between adjacent cylinders 2, as shown. This arrangement is one in which the branch pipes 10 and nozzles are so situated that they do not interfere with the operator introducing his hand into the pocket to feed 115 an end of the web from one cylinder to the next one. We will preferably employ a nozzle which can be collapsed more or less when not in use thus permitting it to be carried still more out of the way than when in its 120 125 130

operative position. In the drawing we have shown the nozzle as supported on a telescopic pipe section 26 which telescopes into the upper end of the portion 20 of the branch pipe 10. The nozzle 9 itself is pivotally mounted on the telescopic pipe section 26, as shown at 27, so that said nozzle can be turned back into line with the pipe section, as shown by dotted lines Fig. 4. 5 This nozzle is shown as made of sheet metal bent into the desired shape and is provided at its rear end with a lip 28 adapted to engage a set screw 29 carried by the upper end of the pipe section. The upper side 30 of 10 the nozzle is curved on an arc struck from the pivot 27 as a center so that the nozzle can swing back on its axis into its inoperative position. The construction herein shown operates also as a means for drying the felt aprons 6 and 7, for it will be seen from Fig. 1 that the air currents which pass through the pockets will act on the portion of each felt apron that is separated from the web of paper and passes over the rolls 8. The air currents thus have a drying 20 effect not only on the web of paper but also on the felt. This is a very great advantage because it prevents the felt from becoming unduly wet.

In the construction shown in Fig. 1 the 25 felt aprons 6 and 7 pass over direction pulleys 8 and said aprons have formed therein pockets 31 which are commonly referred to in this art as the felt pockets. We 30 have provided herein means for delivering air currents through these felt pockets to assist in drying the felt, and the air currents which thus pass through the felt pockets are of the same nature as those which pass through the pockets 4 and 5, that 35 is, they are formed from a current-inducing air current commingled with an air current induced by the first-named current. In order to secure this effect, we provide each 40 of the branch pipes 10 with a nozzle 32 directed toward the adjacent felt pocket 31, said nozzle delivering into said pocket a current of air designated by the arrows 33. This current of air 33 induces a current of 45 room air designated by the arrows 34, and the two combined currents passing through the pocket 31 assist in drying the felt apron. The walls of each pocket 31 together with the nozzle 32 constitute a sort of injector 50 apparatus by which a drying current of air 55 can be forced through each of the felt pockets with a minimum expenditure of power.

While we have illustrated herein our invention as applied to a drying apparatus of 60 a paper-making machine, we do not wish to be limited to its use in this connection, as it will be obvious that the principle of the invention may be applied to different devices where the web to be dried passes over supports which form in said web one or more

65 pockets arranged so that the injector action above described can be secured.

We claim:

1. In a drying apparatus, the combination with a plurality of supporting members over which a web to be dried is adapted to travel and which are arranged to form a plurality of pockets in the web supported thereby, of means to deliver a current-inducing air current into each pocket from 70 the end thereof and in a position to impinge against the web at a point intermediate of its edges and to induce a current of room air into and through the pocket over the surface of the web. 75

2. In a device of the class described, the combination with a plurality of supporting members over which a web to be dried is adapted to travel and which are arranged to form a plurality of pockets in the web supported thereby, of a nozzle situated at 80 the end of and exterior to each pocket and disposed to deliver a current-inducing air current into said pocket in a direction to impinge against the web intermediate of its 85 edges and to induce a current of room air into and through the pocket over the surface of said web. 90

3. In a device of the class described, the combination with a plurality of supporting 95 members over which a web to be dried is adapted to travel and which are arranged to form a plurality of pockets in the web supported thereby, of means situated at the end of and exterior to each pocket to deliver thereinto and over the surface of the web forming the walls of the pocket remote from said means a current-inducing blast of air and to induce a current of room air over the portion of the web adjacent said 100 means. 105

4. The step in the method of drying a web which is traveling over supporting members arranged to form pockets in said web which consists in subjecting a portion 110 of the area of the web to the action of a blast of drying air and the rest of said area to the action of a current of room air induced by the blast of air.

5. The steps in the process of drying a 115 web of material which is traveling over a plurality of cylinders arranged to form pockets in the web which consists in delivering a current of air into each pocket against the web forming the wall thereof at 120 a point intermediate of the edges of the web and at an angle thereto and inducing a current of room air into the pocket over the surface of the web not affected by the first-named current of air. 125

6. In an apparatus of the class described, the combination with upper and lower cylinders over which a web is adapted to travel thereby forming a series of pockets beneath the upper cylinders and between the ad- 130

adjacent lower cylinders, of means to deliver into the pockets current-inducing currents of dry air in a direction to impinge against the web forming the sides of the pockets at

5 points between the edges of the web and to induce currents of room air across the portion of the web not exposed to the current-inducing air current.

7. In an apparatus of the class described, 10 the combination with upper and lower cylinders over which a web is adapted to travel thereby forming a series of pockets beneath the upper cylinder and between the adjacent lower cylinders, of means situated 15 entirely outside of the pockets to deliver into the pockets current-inducing currents of dry air in a direction to impinge against the web forming the sides of the pockets at points between the edges of the web and to 20 induce currents of room air across the portion of the web not exposed to the current-inducing air current.

8. In an apparatus for drying, the combination with upper and lower cylinders over 25 which a web is adapted to travel thereby forming a series of pockets above the lower cylinders and between the adjacent upper cylinders, of means to deliver into the pockets current-inducing currents of dry air in 30 a direction to impinge against the web forming the sides of the pockets at points between the edges of the web and to induce currents of room air across the portion of the web not exposed to the current-inducing 35 air current.

9. In an apparatus for drying, the combination with upper and lower cylinders over which a web is adapted to travel thereby forming a series of pockets beneath the 40 upper cylinders and above the lower cylinders, of a nozzle situated at the end of each pocket exterior thereto and having two divergent discharge openings arranged to direct a current of air issuing therefrom 45 against the web forming the sides of the pockets at points intermediate of the edges of the web, and means to supply air under pressure to said nozzles.

10. In a device of the class described, the 50 combination with supporting members over which a web to be dried is adapted to travel and which are arranged to form pockets in said web, of an air supply pipe leading to each pocket, and a nozzle connected to each 55 air supply pipe but situated exterior of the corresponding pocket and provided with

means to deliver an air current against the sides of the pocket at an angle thereto, each nozzle having a telescopic engagement with its supply pipe.

60

11. In a device of the class described, the combination with supporting members over which a web to be dried is adapted to travel and which are arranged to form pockets in said web, of an air supply pipe leading to 65 each pocket, and a laterally-projecting nozzle pivoted to each supply pipe and adapted to be turned from its operative position directly toward the pocket into its inoperative position in alinement with the supply pipe. 70

12. In a drying apparatus, the combination with a plurality of supporting members over which a web to be dried is adapted to travel and which are arranged to form one or more pockets in the web supported thereby, of means to deliver a current-inducing air current into each pocket and to induce a current of room air into and through the 75 pocket over the surface of the web.

13. In a device of the class described, the 80 combination with a plurality of supporting members over which a web to be dried is adapted to travel and which are arranged to form a plurality of pockets in the web supported thereby, of means situated adjacent one end of each pocket to deliver thereinto and over the surface of the web forming the walls thereof remote from said means a current-inducing blast of air thereby to induce a current of room air over the portion 85 of the web adjacent said means.

14. In an apparatus of the class described, the combination with means to support a traveling web to be dried and arranged to form a pocket in said web, of means to deliver a current-inducing air current into 90 said pocket from one end thereof and in a direction to induce a current of room air through said pocket from said end to the other end thereof whereby the web will be 100 dried partly by the induced current of room air and partly by the current-inducing air current.

In testimony whereof, we have signed our names to this specification, in the presence 105 of two subscribing witnesses.
